ARTHUR H. MAYNARD, OF WARWICK, RHODE ISLAND, ASSIGNOR TO BOSTON WIRE STITCHER COMPANY, OF PORTLAND, MAINE, A CORPORATION OF MAINE.

WORK-GUIDE FOR WIRE-STITCHING MACHINES.

1,272,694.

Specification of Letters Patent. Patented July 16, 1918.

Application filed January 13, 1916. Serial No. 71,880.

To all whom it may concern:

Be it known that I, ARTHUR H. MAYNARD, a citizen of the United States, residing at Warwick, in the county of Kent, State of Rhode Island, have invented certain new and useful Improvements in Work-Guides for Wire-Stitching Machines, of which the following is a specification.

My invention is an improved work-guide for use on wire-stitching machines employed in stitching together the flaps of cartons in the manufacture of knock-down boxes or similar articles. The object of my improvement is to provide means for guiding the carton blanks through the machine in position to be operated upon by the stitching mechanism while allowing the work to be fed continuously forward, without reversing the direction of its feed, whereby the stitching operation may be accomplished more conveniently and expeditiously.

The invention is fully described in the following specification, illustrated by the accompanying drawings, in which like reference characters designate like parts.

In the drawings:—

Figure 1 is a side elevation of a stitching-machine showing my improved work-guide applied to use in connection therewith; Fig. 2 is a perspective view of the work-guide; and Fig. 3 is a longitudinal elevation of the same.

Referring first to Fig. 1, I have here illustrated a well-known type of wire-stitcher or stapling-machine as employed for stitching or fastening together sheets of cardboard in the manufacture of collapsible cartons or similar articles. It is to be understood, however, that my present improvement is adapted for different styles of machines from that here shown and is also applicable to other character of work than that herein described.

The machine here illustrated comprises essentially the stitcher-head A supporting a bonnet B, in which are mounted the staple-forming and driving-mechanisms, and a work-support or table T arranged underneath. Mounted rotatively on the head A is a supply-spool W from which the wire w for forming the staples delivers over a rib-

bon-like guide G, and thence leads down through the bonnet B. The staple-stitching mechanism contained within the bonnet B may be of any preferred arrangement, such 55 for instance as that described in United States Letters Patent No. 970,461, granted to Thomas A. Briggs, Sept. 20, 1910, but this part of the machine not being essential to an understanding of the present invention it 60 will not be herein described in detail. Suffice to state that the machine operates in the well-known manner to cut the wire w into lengths which are formed into staples to be driven through the work and clenched 65 thereagainst to secure the parts together.

As before explained, my improved work-guide is intended for use particularly in stitching together the flaps or sides of collapsible carton blanks which are adapted 70 to be folded flat or opened out in rectangular shape. Referring to Fig. 1, the blank C for the carton comprises the four flaps or sides c, c', c² and c³ which are here shown as folded together in a substantially flat, tubular form. The flap c corresponds in dimensions to the side c² and the side c' to the side c³ so that when the blank is opened out they assume positions opposite each other to form the sides and ends of the carton. That is to 75 say, the flap c is folded back at right-angles to the flap c' and the flap c² is then bent on the scored line indicated at x, Fig. 1, to cause it to stand parallel with and opposite the side c. The flap c³ is then bent into position parallel with the side c' and extending 80 between the sides c and c². In this way a rectangular figure is formed with the flaps constituting the sides of the box, lacking the bottom and top. It will be noted that the 85 cardboard of the blank C is scored at x to adapt it to be folded at this point to provide a relatively narrow flap c⁴ by which the side c is attached to the side c³. The flap c⁴ is employed as a sort of corner-stay, 90 being adapted to overlap the edge of the side c and serve as a means for fastening it to the side c³. For this purpose the marginal edge of the side c is usually stitched 95 to the flap c⁴ with wire staples spaced a slight distance apart along the seam. The 100 essential feature of the present invention is

the arrangement of the work-guide which permits the feeding of the blanks C through the machine with their sides in folded relation as illustrated in Fig. 1, while providing for fastening together the overlapping edges of the side c and flap c⁴ without stitching through the underlying side c'. To this end my improved guiding-device is constructed as follows:

- 10 Referring to Fig. 2, the work-guide comprises essentially a lower support or plate D adapted to be supported in spaced relation above the horizontal table T of the machine, as shown in Fig. 1, with its inner end directly beneath the staple-driving mechanism of the bonnet B, see also Fig. 3. At this end the upper face of the plate D is provided with two crescent-shaped grooves or depressions d, d spaced slightly apart on 15 the median line of the plate, and adapted to receive the legs of the staple as they are driven down through the work to bend them over and clench their ends against the under side thereof. Secured to the longitudinal 20 edge of the plate D at its forward end is a cleat or side-rest E of relatively greater thickness than the plate. The forward end of the cleat E is preferably rounded off on its inner side at e to avoid a sharp corner 25 which might interfere with the blank as it is fed into the guide as later explained. The cleat E might be constructed as an integral part of the plate D, but for the sake of economy in manufacture it is preferably 30 made separate therefrom and attached thereto by any suitable means such, for instance, as the screws s, s having their heads countersunk into the under side of the plate D as shown more particularly in Fig. 3. 35 Let into the top of the cleat E, so that its upper face comes flush therewith, is an overlying top-plate F which extends clear across the width of the plate D throughout the central portion thereof. The top-plate F is 40 secured to the cleat E by the rivets r, r, shown in Fig. 3 or through any other suitable means, and is supported thereby in parallel relation to the plate D, overlying its upper face. The rear portion of the 45 plate F is preferably inclined upwardly at a slight angle to its forward, horizontal portion by being bent on a line coincident with the end of the cleat E. At its rear or inner end the plate F is bent upwardly at 50 a right-angle to its main, horizontal portion to form a vertical web or flange f by means of which the whole guide is attached to the head A of the machine. Referring to Figs. 1 and 3, two screws v, v extend 55 through suitable holes f', f' in the flange f, see Fig. 2, and are screwed into the side of the bonnet B to fasten the guide in place on the head A. At the right-hand, forward end of the plate F is an extension or lip f² 60

bent upwardly at an angle, as shown more 65 particularly in Figs. 2 and 3, and serving as a guiding-element to direct the flap c³ of the blank C under the plate F as it is fed through the guide. The lip f² extends approximately half way across the width of 70 the plate F so as to clear the edge of the flap c of the blank C which feeds across the top of the upper plate at the left-hand side, as shown in Fig. 1.

Near its center the left-hand portion of 75 the plate F is slit across at f³ and then rearwardly at f⁴ to the bend of the upstanding flange f. The slotted portion f⁵ of the plate F thus cut away is bent or curled upwardly as shown in Fig. 3 to form an entrance for the side c of the blank to direct it down under the stitching-mechanism of the bonnet B. That is to say, the inclined apron-like portion f⁵ of the plate F acts as a guard or deflector to guide the flap c 85 in under the staple-driving devices in proper relation thereto so as to prevent it from striking against the side of the bonnet B and being obstructed thereby during the feeding of the blank through the machine. 90

The method of constructing the work-guide in several sections as above described makes for economy in manufacture and also renders the lower portion D detachable to allow for its replacement or the substitution 95 of other clencher-plates of different form. For instance, with other types of machines different forms of clencher-means might be required which could be constructed as a part of the attachable plate 100 D or arranged to be fitted thereto. It will be obvious, however, that the method of constructing the parts of the work-guide is not important, but could be varied slightly without departing from the 105 spirit or scope of the invention. For instance, the two plates D and F might be made in one piece from sheet-metal folded or bent along the side. With this construction the folded-over portion of the upper 110 plate F would be extended along the side of the lower plate D clear to its front edge, while being made relatively narrow on the top to correspond to the dimensions of the 115 cleat E. That is to say, a forwardly projecting strip from the upper, folded plate F would serve the same purpose as the solid cleat or side-rest E.

Having now described the construction and arrangement of my improved work-guide and its method of operation will next be explained. The carton blank C is placed in the machine with the flaps or sides c', c² resting on the work-table T, while the flaps c and c³ are bent upwardly at x² and x⁴. At 125 the right-hand side of the table T is a side-register or guide H which is adjustable in position for different sizes of blanks to reg-

ulate their position in relation to the stitching-mechanism of the machine. The folded edge c^4 of the blank C is first placed against the guide H and as the blank is pushed forward toward the head A the flap c is folded over on top of the cleat or side-rest E while the flap c^3 is rested upon the lower plate D. This will bring the marginal edge of the flap c directly above the narrow flap c^4 , which is joined to the edge of the flap c^3 , so that these two portions of the blank will be brought into proper relation to be fastened together as they feed under the stapling-mechanism. The blank C is now pushed forward through the work-guide and as its leading end meets the edge of the top-plate F the flap c will be guided by the rest E onto the top thereof, while the flap c^3 will be deflected by the lip f^2 in under the plate F. In other words, the folded flap c will ride along the rest or cleat E onto the top of the plate F, while the flap c^3 will feed along the top of the lower plate D underneath the plate F. The flap c^3 naturally has a tendency to spring upwardly from its folded edge c^4 and it is to overcome this tendency and prevent the flap from striking against the front edge of the plate F that the guiding-lip f^2 is provided. In brief, the lip f^2 acts as a guard to deflect the flap c^3 downwardly to insure its passing below the plate F.

As the blank C is fed still farther forward in the work-guide the leading edge of the flap c will slide under the inclined apron f^5 , as shown in Fig. 1. Through this means the flap c is directed downwardly under the rear end of the plate F to cause it to pass out through the guide below the stitching-mechanism on the bonnet B. In this manner the flap c is brought into position under the staple-driving devices with its marginal edge resting on the fastening flap c^4 . Now, as the machine is operated in the usual manner the wire staples will be driven down through the overlapping portion of the flaps c and c^4 to stitch them together. As the staples S are driven through the work, as shown in Fig. 3, the ends of their legs are met by the plate D and received in the slots d , d to cause them to be bent over and clenched into place against the under side of the flap c^4 . As the staple-driving mechanism descends on the upper flap c it presses it down against the flap c^4 which, in turn, is pressed down against the plate D. The plate D is therefore forced down against the under flap c' of the blank C to hold the latter against the table T and prevent the whole blank from being displaced. After the pressure of the staple-driving mechanism is removed, the plate D springs upwardly again to clear it from the under flap c' of the blank so that the latter

is then free to be fed forward again into position for receiving the next staple. In this way the inner end of the plate D acts as the fixed clencher-means for bending and clenching the ends of the staples into place while holding the blank C in fixed position during the stitching operation and also preventing the machine from stitching clear through the under flap c . It will thus be seen that my improved work-guide enables the operator to feed the blanks continuously forward through the machine to stitch the edges of the flaps together without reversing the direction of the feed. In brief, the work-guide acts to direct the flaps of the blank into proper position in relation to each other and to the stitching-mechanism while also preventing the flaps from springing up out of place and being obstructed by the parts of the machine.

I am aware that it has before been proposed to employ a work-guide on stitching-machines adapted to provide for a continuous feeding of tubular blanks under the stitching-mechanism to fasten their marginal edges together. It will be understood, therefore, that I do not claim such a work-guide broadly but only the novel arrangement of the device as herein shown and described. It is believed that the present arrangement is an improvement over previous devices employed for like purposes in that a more complete control is maintained on the blank as it is fed through the machine and therefore less care or attention is required of the operator. In other words, the present device is intended particularly to insure a proper feeding of the blanks to the stitching-mechanism of the machine without requiring particular skill or care on the part of the operator.

What I claim is: —

1. In a work-guide for wire-stitching machines, the combination with a lower horizontal work-support, of an upper plate overlying the support in parallel spaced relation thereabove and joined thereto along its longitudinal side, said plate bent upwardly at its rearward end to form a vertical flange extending laterally across the plate at right-angles to its longitudinal side to provide a fastening-means for attaching the work-guide to the machine.

2. In a work-guide for wire-stitching machines, the combination with a lower horizontal work support, of an upper plate overlying the support in spaced relation thereabove and joined thereto along its longitudinal side, said plate formed with a vertical flange extending laterally across its rearward end to provide a fastening means for attaching it to the machine and having a cut out portion extending across a portion of its width to guide the work downwardly

against the rearward end of the lower support.

3. In a work-guide for wire stitching machines, the combination with a lower horizontal plate, of a top-plate spaced above and overlying the lower plate, said top-plate joined to the lower plate along its longitudinal edge and provided with a slotted portion inclined upwardly from its horizontal plane to form a guard for directing the work down under the rear end of the top-plate after it feeds across the front portion thereof.

4. In a work-guide for wire-stitching machines, the combination with a lower horizontal clencher-plate, of a cleat attached to a longitudinal edge of said plate and extending rearwardly from the forward end of said plate, and a top-plate secured at one side to the top of the cleat to overlie the clencher-plate in spaced relation therewith, said top-plate bent upwardly at its rearward end to form a vertical flange extending laterally thereacross to provide a means for fastening the guide to the machine.

5. In a work-guide for wire-stitching machines, the combination with a lower horizontal clencher-plate, of a cleat attached to said plate along its longitudinal edge, and a top-plate extending from the side of the cleat to overlie the clencher-plate in spaced relation thereto, said top-plate formed with an opening at its side and having an inclined apron bent upwardly therefrom to act as a guard to deflect the work down into position above the clencher-plate.

6. In a work-guide for wire-stitching machines, the combination with a lower horizontal plate, of a top-plate spaced above and overlying the lower plate, said top-plate joined to the lower plate along its longitudinal edge and bent upwardly at the rear to provide a vertical web for attaching it to the machine, one side of the plate being slotted laterally and then rearwardly to form a cut out apron which is bent upwardly from the main plane of the plate to provide an inclined guard for directing the work down under the rear end of the top-plate.

50 7. In a work-guide for wire-stitching machines, the combination with a horizontal clencher-plate provided with staple-receiving grooves at its rearward end, of a top-plate spaced above and overlying the central portion of the clencher-plate, said top-plate joined to the clencher-plate along its longitudinal edge and cut away laterally from its side across a part of its width to provide an opening for receiving the work to pass it down under the rear portion of the top-plate into position above the staple-receiving grooves on the clencher-plate.

8. In a work-guide for wire-stitching machines, the combination of two horizontal

plates spaced one above the other and joined together at the side along a portion of their longitudinal edges, the upper overlying plate being formed with a laterally-extending vertical web at its rear and having an upwardly-inclined guiding-lip projecting from its forward end across a part of the width thereof, the longitudinal side of said upper plate being slotted laterally and then rearwardly to provide a cut out apron which is bent upwardly to form an inclined guard for deflecting the work in under the rear portion of the plate.

9. In a work-guide for wire-stitching machines, the combination with a lower horizontal plate, of a top-plate spaced above and overlying the central portion of the horizontal plate, said top-plate joined to the lower plate along its longitudinal edge and slotted laterally and rearwardly at its side to provide a cut out apron which is bent upwardly to form an inclined guard to deflect the work down under the rear end of the top-plate, and an extension on the forward end of the top-plate bent upwardly to provide a guiding lip to direct one side of the work under the front edge of the top-plate.

10. In a wire-stitching machine having a stitcher head for fastening together the flaps of carton blanks, the combination of a horizontal clencher-plate arranged with its rearward end beneath the stitcher head, and a top-plate spaced above and overlying the clencher-plate, said top-plate joined to the clencher-plate along its longitudinal edge and attached to the stitcher-head at its rearward end to support the parts in operative relation thereto, and said top-plate cut away on its side across a portion of its width to provide an opening through which the work is fed to bring it into position beneath the stitcher-head.

11. In a wire-stitching machine having a stitcher-head for fastening together the flaps of carton blanks, the combination of a horizontal clencher-plate arranged with its rearward end beneath the stitcher-head, and a top-plate spaced above and overlying a portion of the clencher-plate with its longitudinal edge joined thereto at one side, said top-plate secured to the side of the stitcher-head at its rearward end to support the parts in operative relation to the stitcher-head and provided with an opening in its side and having an inclined apron projecting upwardly from said opening to direct the work down under the stitcher-head.

12. In a wire-stitching machine having a stitcher-head, the combination of a horizontal clencher-plate arranged beneath the stitcher-head and extending forwardly therefrom, and a top-plate spaced above and

overlying the central portion of the clencher-plate, said top-plate joined to the clencher-plate along its longitudinal edge and formed with an upstanding flange attached to the 5 stitcher-head to support the parts in opera-tive relation therewith, said top-plate slotted laterally and rearwardly at one side with the cut out portion providing an apron bent upwardly at its front to adapt it to deflect

the work under the stitcher-head as it is fed 10 thereto.

In testimony whereof I affix my signature in presence of two witnesses.

ARTHUR H. MAYNARD.
